UNITED STATES PATENT OFFICE.

J. HAMILTON SHAPLEY, OF EXETER, NEW HAMPSHIRE.

IMPROVEMENT IN GUN-LOCKS.

Specification forming part of Letters Patent No. 39,501, dated August 11, 1863.

To all whom it may concern:

Be it known that I, J. HAMILTON SHAPLEY, of Exeter, in the county of Rockingham and State of New Hampshire, have invented a new and useful improvement for side locks with horizontal or sidewise motion of the hammer for fire-arms; and I do hereby declare that the following is a full, clear, and exact description of the construction and operation of the same, reference being had to the accompanying drawings, making a part of this specification, of which—

Figure 1 is a perspective view of the interior of a lock; Fig. 2, the hammer and the different parts connected therewith; Fig. 3, the dog or sear and the different parts of it.

In Fig. 1, the letters A B C D represent the plate, on which two shoulders or flanges, E' E'', are constructed lengthwise of the plate, with a space between the flanges and an aperture or hole through the plate between them, but not as long as the flanges. In one end of both flanges spaces or slots are cut, as at G.

Fig. 2 represents the hammer and the different parts connected therewith, of which R is the hammer; S, the shank, L, the heel; T' T'', notches on the front of the heel; U, the screw or pin hole on which the hammer turns, and W a curvilinear projection from the back of the heel, against which the mainspring M operates to throw the hammer forward.

In Fig. 3, H' H'' H''' represent the sear; I I, the side arm, and J another arm at right angles horizontally with I I, and Q the nose of the sear, and in the side arm, I I, is a small slot. Through the face of the plate the heel L, Fig. 2, of the hammer is inserted between the flanges on the inner side of the plate, and there secured by a screw-pin, O, Fig. 1, passing through the flanges and heel of the hammer at U, Fig. 2. The sear H' H'' H''', Fig. 3, is perpendicular and at right angles to the arm I I, and the arm J is at right angles and

horizontal to the arm I I. Projecting from the part H' H'' H''' is a nose, Q, forming an obtuse angle with H'', and of the width of the space between the flanges where it plays. H' and H''' of the sear are placed in the slots G in the ends of the flanges, which brings the nose Q of the sear to the notches T' and T'' on the front of the heel of the hammer. The sear is secured in its place by the arm I I, passing along the side of the flange E''. In the arm I I is a slot, through which a small screw, P, passes into the flange E'', and on this screw the arm I I slides. The trigger of the rifle or gun rests against the back of the arm J. When the hammer is pulled half back or half-cocked, the nose of the sear is, by the spring K, (which is secured by a screw to the side of the flange E' at F—the end of the spring presses against the sear at H',) pressed into the bent T', and there secures the hammer at the half-cock. On again pulling the hammer farther back, the nose Q of the sear is pressed into the bent T'', where the hammer is there held by the nose Q of the sear, at full-cock. By pulling the trigger against the arm J, it presses the arm I I and the sear H' H'' H''' forward, which relieves the nose of the sear from the notches of the hammer, and the force of the mainspring M throws the hammer forward upon the cap, to explode it.

The shape of the plate and of the hammer may be made of any fancy design.

What I claim as my invention, and desire to secure by Letters Patent, is—

The sear and the nose of the sear and all its parts, which are fully above described, or their equivalent, and the mode of using or applying the same.

Exeter, New Hampshire, July 10, 1863.

J. HAMILTON SHAPLEY.
